UNITED STATES PATENT OFFICE.

GEORGE W. MEYERS, OF CHICAGO, ILLINOIS, ASSIGNOR OF ONE-HALF TO ERWIN W. RINDER, OF CHICAGO, ILLINOIS.

DESIGN FOR AN INDIRECT-LIGHTING FIXTURE.

45,539.

Specification for Design.

Patented Mar. 31, 1914.

Application filed February 5, 1913. Serial No. 746,384. Term of patent 7 years.

To all whom it may concern:

Be it known that I, GEORGE W. MEYERS, a citizen of the United States, residing at Chicago, in the county of Cook and State of Illinois, have invented a new, original, and ornamental Design for Indirect-Lighting Fixtures, of which the following is a specification, reference being had to the accompanying drawing, forming part thereof.

Figure 1 is a side elevation of an indirect lighting fixture showing my new design;

Fig. 2 is a bottom plan of the same; and Fig. 3 is a cross section illustrating the appearance of the fixture from the several directions.

I claim:

The ornamental design for an indirect lighting fixture, as shown.

GEORGE W. MEYERS.
